UNITED STATES PATENT OFFICE.

JOHN PIERCE, OF MILTON, MASSACHUSETTS, ASSIGNOR OF TWO-THIRDS
TO JOSEPH H. CHADBOURNE, OF WATERTOWN, MASSACHUSETTS, AND
WALTER B. MOORE, OF SWAMPSCOTT, MASSACHUSETTS.

STOP FOR LACING-HOOK-SETTING MACHINES.

SPECIFICATION forming part of Letters Patent No. 739,106, dated September 15, 1903.

Application filed December 29, 1902. Serial No. 136,974. (No model.)

To all whom it may concern:

Be it known that I, JOHN PIERCE, a citizen of the United States, residing at Milton, in the county of Norfolk and State of Massachusetts, have invented new and useful Improvements 5 in Stops for Lacing-Hook-Setting Machines, of which the following is a specification.

This invention relates to that class of machines in which articles—such as lacing-hooks, buttons, rivets, and the like—are fed from the hopper to a raceway and are taken from the raceway one by one after being set or attached to a piece of sheet material. I have illustrated and described my invention as 10 adapted to a machine for setting lacing-hooks, said machine being substantially the same as that for which I have obtained Letters Patent of the United States, dated July 9, 1901, No. 678,028, with the exception that the 15 stop for the lacing-hooks is provided with a spring-latch, the object of said latch being to yield and allow the lacing-hook to be drawn past the stop on the raceway; and, further, the object of the invention is to prevent the 20 lacing-hook from being jammed in cases where the operator has not moved the lacing-hook set in the material beyond the stop before said stop arrives at its lowermost position, so that the lower edge of the stop strikes 25 upon the top of the lacing-hook. The yielding latch pivoted to the stop prevents marring the hook in this latter case.

The invention consists, in a machine of the character described, of a raceway, an anvil, 30 a pivotally-mounted stop located at one side of a plane extending through the center of said anvil and intersecting the path of the lacing-hooks on said raceway as they approach said anvil, a spring-latch pivoted to 35 said stop, and mechanism for imparting a rocking motion to said stop.

The invention, again, consists, in a machine for setting lacing-hooks and the like in sheet material, of the combination of an anvil, a 40 plunger, mechanism for imparting a reciprocating motion to said plunger, a raceway fast to said plunger, a stop pivoted to said plunger, a spring-latch pivoted to said stop and normally projecting below the lower edge thereof,

and mechanism to impart a rocking motion 50 to said stop.

The invention further consists in the combination and arrangement of parts set forth in the following specification and particularly pointed out in the claims thereof. 55

Referring to the drawings, Figure 1 is a right-hand side elevation of a portion of a lacing-hook-setting machine similar to that shown and described in my United States Letters Patent No. 657,673, with the improved 60 stop forming the subject-matter of this application attached thereto. Fig. 2 is a vertical sectional elevation taken on line 2 2 of Fig. 1 looking toward the left in said figure. Fig. 3 is a rear elevation of a portion of the 65 plunger, raceway, separator, and stop, with a number of lacing-hooks on said raceway, the same being shown full size and starting to descend. Fig. 4 is a view similar to Fig. 3, with the parts shown in the relative positions 70 assumed when the plunger is in its lowermost position and the lacing-hook set in the material is being moved by the operator along the raceway. Fig. 5 is an enlarged right-hand side elevation of the parts shown in 75 Fig. 3. Fig. 6 is a side elevation of the parts shown in Fig. 4. Fig. 7 is a detail section on line 7 7 of Fig. 5. Fig. 8 is an enlarged right-hand side elevation of my improved stop. Fig. 9 is a left-hand side elevation of the 80 same. Fig. 10 is a perspective view of the separator-plate, lock-plate, and rocker-shaft.

Like numerals refer to like parts throughout the several views of the drawings.

In the drawings, 11 is the frame of a lacing-hook-setting machine similar to that shown and described in Patent No. 657,673, hereinbefore referred to. 85

12 is a reciprocating plunger arranged to slide in bearings 13 13 and having a reciprocating motion imparted thereto by a lever 14, pivoted at 15 to the frame 11. 90

The lacing-hooks are delivered from a hopper 16 by a picker-plate 17 to a raceway 18, fast to the plunger 12. Said raceway extends 95 vertically downward from the hopper 16 and is bent at right angles at the bottom 19 thereof to a horizontal position beneath the plun-

ger 12. In the lower part of the plunger 12 is a rock-shaft 20, having fast thereto a separator-plate 21 and a stop 22, said stop and separator being located upon opposite sides 5 of a vertical plane passing through the center of the anvil 38 and intersecting the path of the hooks on the raceway as they approach the anvil. Between the stop 22 and the plunger 12 is a spring-washer 23, which holds said separator, rock-shaft, and stop in any position to which they may be moved, as hereininafter described. The stop 22 has a finger 24 thereon, which abuts against a stop 25, fast to the frame of the machine, when the plunger 12 and raceway 18 are nearly arrived at their lowermost positions, tipping the stop and the separator from the position shown in Fig. 5 to that shown in Fig. 6. When the plunger 12 and raceway 18 ascend, together 15 with the separator and stop-plate 22, a pin 26, fast to the stop-plate 22, strikes against the frame 11 of the machine and rocks the separator 21 and stop-plate 22, together with the rock-shaft 20, from the position shown in Fig. 6 to that shown in Fig. 5. The stop-plate 22 is provided with a flattened surface 27 upon its lower edge and with another flattened surface 28.

A latch 29 is pivoted at 30 to the plate 22 20 and is located in a recess 31, provided in said stop-plate. Said latch has a shoulder 32 thereon, which abuts against a shoulder 33, provided on the stop-plate 22, and is normally held against said shoulder 33 by a flat spring 34, located in the recess 31. The latch 29 is beveled at 35 upon the side thereof adjacent to the anvil and upon the lower edge of said latch.

The operation of my improved rocking stop 30 in conjunction with the vertically-reciprocating plunger, raceway, and separator-plate is as follows: The lacing-hooks are delivered to the raceway 18 from the picker-plate 17 and slide down said raceway to the position shown 35 in Fig. 3. The lowermost lacing-hook 36 resting upon the short horizontal portion 19 of the raceway 18, with the left side of the head of said lacing-hook touching the right side of the latch 29 upon the stop-plate 22, 40 the weight of the hook 37 and the column of hooks on the raceway pushes the hook 36 into the position shown in Figs. 2 and 3 and brings said hook into a vertical position directly above the center of the anvil 38. The plunger 12 is shown raised in Figs. 2 and 3 and just 45 beginning to descend. The operator next places the upper of the shoe in the proper position over the anvil 38, Fig. 2, and the plunger descends. As the plunger descends the rock-shaft 20, with the stop and separator plates fast thereto, remains stationary with 50 relation to the plunger and raceway until just before the shank of the lacing-hook 36 abuts against the upper face of the leather of the shoe-upper, when the finger 24 strikes the stop 25 and tips the separator and stop-plates 21 and 22, respectively, together with the rock-

shaft 20, from the position shown in Fig. 5 to that shown in Fig. 6. During the last part of the downward motion of the plunger the 55 shank of the lacing-hook 36 is driven through the shoe-upper 39 and clenched upon the anvil 38. It will be seen that when the plunger and raceway, together with the separator-plate, stop-plate, and rock-shaft, start to ascend the lowermost lacing-hook can be removed 60 from the raceway at any time after said lacing-hook has cleared the top of the anvil 38 and until the pin 26 strikes the frame 11 of the machine, as the heads of the lacing-hooks 65 are free to pass along the horizontal portion of the raceway and beneath the flat surface 28 upon the stop-plate 22 without contacting with said stop-plate. At the last part of the upward motion of the plunger the position of 70 the separator and stop plates will be reversed and the depression 40 in the periphery of the separator-plate will come in line with the lacing-hooks upon the raceway, allowing the lowermost hook in the column of hooks on the raceway to pass down said raceway and against the right-hand side of the latch 29, which by that time will have been rocked 75 into position in line with the lacing-hooks upon said raceway. It will also be seen that 80 the lowermost hook in the column of hooks on the raceway has all of the time occupied by the plunger in descending from its uppermost position to the point at which the finger 24 encounters the stop 25 in which to travel 85 along said raceway to a position immediately above the anvil 38 and between the separator and stop plates. It will further be seen and understood that the rocking of the shaft 20 and of the stop and separator plates fast 90 to the stop-plate takes place just as the lacing-hook enters the upper 39 of the shoe, so that the head of said lacing-hook is held between the separator and stop plates as the shank of the lacing-hook first enters the upper and while 95 it is passing through it, and thus holds said lacing-hook firmly in position during the setting operation.

It will be particularly noted, as hereinbefore set forth, that with a stop-plate constructed as hereinbefore described, having a spring-latch pivoted thereto and projecting below the lower edge of said stop-plate, the lacing-hook, which has been set in the upper, as hereinbefore described, may be removed 100 from the horizontal portion of the raceway by the operator at any time after the shank of the lacing-hook has cleared the top of the anvil. During the upward motion of the plunger, as hereinbefore described, the top 105 of the lacing-hook is free to be removed from the raceway as soon as said lacing-hook clears the anvil 19. When the stop-plate has been tipped, as hereinbefore described, from the position shown in Fig. 6 to that shown in Fig. 5 at the extreme of its upward movement and during its downward movement, the lacing-hook 36 may be removed by the operator 110 by pulling the upper, together with said lac-

ing-hook, past the latch 29, said latch yielding to allow the head of the lacing-hook to pass thereby, this operation being facilitated by the beveled edge 35 upon the inner and 5 lower edge of said latch, and, further, it will be noted that if through mistake of the operator or inaccuracy in feeding the upper by said operator a lacing-hook should come beneath the stop when said stop is nearing its 10 lowermost position and the latch 29 should come in contact with the top of said lacing-hook then said latch will yield without injuring said lacing-hook.

Having thus described my invention, what 15 I claim, and desire to secure by Letters Patent, is—

1. In a machine for attaching lacing-hooks and the like to sheet material, an anvil, a raceway, a pivotally-mounted stop located at 20 one side of a plane extending through the center of said anvil and intersecting the path of the lacing-hooks on said raceway as they approach said anvil, a spring-latch pivoted to said stop, and mechanism for imparting a 25 rocking motion to said stop.

2. In a machine for attaching lacing-hooks and the like to sheet material, an anvil, a plunger, mechanism for imparting a reciprocatory motion to said plunger, a raceway fast 30 to said plunger, a stop pivoted to said plunger, a spring-latch pivoted to said stop and normally projecting below the lower edge thereof, and mechanism to impart a rocking motion to said stop.

3. In a machine for attaching lacing-hooks 35 and the like to sheet material, an anvil, a plunger, mechanism for imparting a reciprocatory motion to said plunger, a raceway bearing a fixed relation thereto, a stop pivoted to said plunger, located at one side of a plane 40 extending through the center of said anvil and intersecting the path of the lacing-hooks on said raceway as they approach said anvil, a spring-latch pivoted to said stop, and mechanism for imparting a rocking motion to said 45 stop.

4. In a machine for attaching lacing-hooks and the like to sheet material, an anvil, a plunger, mechanism for imparting a reciprocatory motion to said plunger, a raceway fast 50 to said plunger, a stop pivoted to said plunger, located at one side of a plane extending through the center of said anvil and intersecting the path of the lacing-hooks on said raceway as they approach said anvil, a spring-latch pivoted to said stop normally projecting below the lower edge thereof, the lower edge of said latch beveled upon the side thereof 55 adjacent to said plane, and mechanism to impart a rocking motion to said stop. 60

In testimony whereof I have hereunto set my hand in presence of two subscribing witnesses.

JOHN PIERCE.
